UNITED STATES PATENT OFFICE.

ALMON B. CALKINS, OF NUTLEY, NEW JERSEY, ASSIGNOR OF FIFTY-ONE ONE-HUNDREDTHS TO CHARLES A. TATUM, OF NEW YORK, N. Y.

INTERNAL-COMBUSTION ENGINE.

1,098,709.

Specification of Letters Patent.

Patented June 2, 1914.

Application filed July 23, 1912. Serial No. 711,038.

To all whom it may concern:

Be it known that I, ALMON B. CALKINS, a citizen of the United States of America, and a resident of Nutley, county of Essex, 5 and State of New Jersey, have invented certain new and useful Improvements in Internal-Combustion Engines, of which the following is a specification, reference being had to the accompanying drawings, forming 10 a part thereof.

This invention relates to a new and improved internal combustion engine of the multiple double acting type which may be used on motor boats, automobiles, trucks 15 and also for aerial propulsion.

An object of this invention is to provide an engine of the type described which will be simple in construction, inexpensive to manufacture, light, compact, well balanced, 20 durable, highly efficient, and giving more power with less weight than has been possible in prior types of internal combustion engines.

Another object of this invention is to 25 produce an internal combustion engine in which the propelling impulses due to the successive explosions will be distributed among a plurality of evenly balanced explosion units so as to produce an evenly balanced torque on the crank shaft.

A further object of this invention is to 30 provide a composite piston comprising a plurality of piston elements secured together so as to move in unison with means 35 for connecting the composite piston to a crank shaft.

A still further object of this invention is to 40 eliminate stuffing boxes, piston rods, and the like, by having each piston element operate in a pair of opposed explosion cylinder units and extending continuous between the pressure actuated ends thereof.

In carrying out these and further objects, a multiple piston is used comprising 45 a plurality of piston elements, each of which cooperates with a plurality of explosion units acting in opposite directions. In this instance, eight explosion units are used quadrantly disposed in pairs. The explosions are arranged so that there will be two 50 explosions on the down stroke and two on the up stroke and these explosions will take place in the diagonally opposed units, so that the thrust on the connecting rod will 55 be well balanced. A particular feature of

this arrangement is in providing each piston unit or element with an integral flange which forms with the other similar flanges, a composite plate or cross head, to which the connecting rod pin can be secured so as to extend in any desired direction. Each piston element extends into two opposed units and is continuous therebetween, so that the use of stuffing boxes, piston rods, and the like is entirely done away with.

Other features and advantages together with the construction and combination of parts will be disclosed more fully hereinafter and particularly set forth in the claims.

Reference may be had to the accompanying drawings forming a part of this specification, in which like reference characters denote corresponding parts, and in which—

Figure 1 is a view in side elevation, Fig. 2 is a fragmentary view in side elevation taken at right angles to the view shown in Fig. 1, to show the exhaust connections. Fig. 3 is a detail view showing the several piston elements and the means for connecting them together to form a composite piston. Fig. 4 is a top plan view, Fig. 5 is a vertical section on line 5—5 of Fig. 4, Fig. 6 is a vertical section on line 6—6 of Fig. 4, Fig. 7 is a vertical section on line 7—7 of Fig. 5, Fig. 8 is a vertical section on line 8—8 of Fig. 5, Fig. 9 is a vertical section on line 9—9 of Fig. 5, Fig. 10 is a vertical section on line 10—10 of Fig. 5, and Fig. 11 is a vertical section on line 11—11 of Fig. 5.

Referring more particularly to the separate parts of this invention as embodied in the form shown in the drawings, 1, 2, 3, 4, 5, 6, 7, 8, represent explosion units of a composite double-acting engine which is adapted to provide the rotary effect for a crank shaft 9. It will be seen that while eight explosion units are shown, more or less might be provided. The explosion units are so arranged, however, that one set of four explosion units are superposed above the other set of four, that is to say, each upper unit has vertically alined therewith a lower unit. Each of these units includes a cylinder open 100 at the end facing the opposed unit, so that in each pair of vertically alined units, a single piston element 10 can act. Each of these piston elements, of which there are four shown, is continuous from end to end 105 110

so that it will be capable of reciprocating with its pressure receiving ends within a pair of opposed cylinder units. Arrangement is made whereby all of the piston elements 10 move in unison, so that they in fact 5 form a composite piston which transmits the propulsion effect given thereto to the crank shaft 9. To accomplish this purpose, there is secured on the crank of the crank shaft 9 10 a connecting rod 11 which extends upwardly to a point where it is provided with a pin 12.

A special feature of this invention is that all of the piston elements 10 can be secured to the connecting rod 11 without interfering with the action of the device as a whole. 15 To accomplish this, each of the piston elements 10 has formed integrally therewith a sector collar or flange 13. These sector flanges 13 of which there is one for each element 10, are four in number and form quadrants which together make up a composite annular member 14, the elements of which may be secured together by means of bolts 15 connecting opposite lugs 16 provided on the juxtaposed flanges. The corner of each flange 13 is cut away so that an internal opening 17 is provided in the composite flange through which the upper end of the connecting rod 11 may extend. The connecting rod pin 12 which is rotatably secured to the upper end of the connecting rod 11, is mounted in a collar 18 which may be adjustably secured in any desired position by means of bolts 19 on the composite 25 flange 14. That is to say, by changing the position of the collar 18, the position of the pin 12 may be changed. The sector flanges together with the piston elements may be integral instead of bolted together, the parts 30 which constitute the body of the rigid piston member being made separate and bolted together in the structure illustrated for convenience in manufacture.

The casing 19^a may be provided for 45 closing the lower explosion units and such portion of the piston elements as are outside of the explosion units, a chamber 20 being left, however, to permit of the reciprocation of the composite flange 14 and the parts 50 connected thereto. Each unit is provided with the usual intake passage 21 for supplying the explosive mixture to the interior of the cylinder and with the usual exhaust passages 22 for emitting the explosive gases to 55 be driven from the cylinders. The intake and exhaust are controlled in any suitable manner as by means of valves 22 which may be actuated from cams 23 through the intermediary of connecting linkages 24. The 60 cams 23 may be driven from the crank shaft 9 in any suitable manner as by having the shafts on which they are mounted connected by any suitable trains of gearing indicated at 25.

65 The several units of the engine are cooled

in a novel manner which will now be described. Each of the units is inclosed in a water jacket 26. The water jackets of the upper set of units 1 to 4 are connected by passages 27 to a common supply pipe 28 70 shown in the form of an annular ring. Similarly, the lower units 5 to 8 have their water jackets supplied by an annular pipe ring 29 which is connected thereto by passages 30. Both of the rings 28 and 29 are divided 75 diametrically, as will be seen by reference to Fig. 11, by partitions 31, so that the circulation is divided to a pair of units in each case. The opposite sides of each ring must, therefore, have inlet supply passages 32 and 80 33, as will be seen by reference to Fig. 11. The water after circulating through the water jackets of the cylinder units may pass through outlet pipes provided at the opposite end of each water jacket for each pair 85 of connected jackets, the jackets being connected in pairs by pipes 34.

The explosive mixture may be supplied to the passages 21 by means of pipes 35 which extend to a common mixing chamber 36 90 which may be connected to any suitable form of carburetor not shown by means of the pipe 37. The bottom of the casing 19 may be formed with muffler chambers 38, so that the exploded gases which are carried off by 95 pipes 39 from the passages 22 may be retarded and the noise of exhaust eliminated.

In the use of the device, the sparking and supplying of the explosive mixture is arranged so that the diagonally opposite units 100 will act in unison, one pair in the upper set acting on one down stroke and the other pair acting on the next down stroke, the same being true of the bottom set, the diagonally opposed pairs acting on the alternate up 105 strokes. For example, the units 1 and 3 will fire while the units 2 and 4 are taking in the explosive mixture on the down stroke. At the same time, the units 6 and 8 are compressing the explosive mixture and the 110 units 5 and 7 are exhausting. On the up stroke 6 and 8 will fire, 5 and 7 take in the explosive mixture, while 1 and 3 will exhaust and 2 and 4 will compress. In the next revolution of the crank shaft, units 2 115 and 4 will fire, while 1 and 3 are taking in the explosive mixture, at the same time that 5 and 7 are compressing and 6 and 8 exhausting. On the succeeding up stroke, units 5 and 7 will fire, 6 and 8 take in the explosive mixture, 1 and 3 compress the mixture, and 2 and 4 exhaust. It will thus be seen that a distributed explosive impulse is imparted to the composite piston, so that the crank shaft will have two impulses in 120 each revolution which impulses are multiple, that is to say, coming from a pair of cylinders on each stroke.

While I have shown one embodiment of my invention, I do not wish to be limited to 125 130

the specific details thereof, but desire to be protected in various changes, alterations and modifications which may come within the scope of the appended claims.

5 Having thus described my invention, I claim as new and desire to secure by Letters Patent:

1. In an internal combustion engine, the combination with a plurality of cylinder units, of a composite piston for acting in said units, said composite piston comprising a plurality of piston elements having integral flanges formed thereon, and means for securing the flanges of all of said piston elements together to form a rigid structure whereby all of the piston elements are connected together in a unified structure, a crank shaft, and a connecting rod pivotally connected with said composite piston and 20 with said crank shaft.

2. In an internal combustion engine, the combination with a plurality of cylinder units, of a plurality of piston units acting in said cylinder units, said cylinder units being arranged in opposed pairs so that each of said piston units can act in two cylinder units to have both ends active, each of said piston units being continuous between its active ends, a sector flange secured to each 30 of said piston elements, means for securing said sector flanges together so as to join said piston units to form a unified composite piston, a crank shaft, a connecting rod, a pin on said connecting rod, and a collar for pivotally supporting said pin on said joined flanges.

3. In an internal combustion engine, the combination with a plurality of cylinder units, of a plurality of piston units acting 40 in said cylinder units, said cylinder units being arranged in opposed pairs so that each of said piston units can act in two cylinder units to have both ends active, each of said piston units being continuous between its 45 active ends, a sector flange secured to each of said piston elements, means for securing said sector flanges together so as to join said piston units to form a unified composite piston, a crank shaft, a connecting rod, a pin 50 on said connecting rod, and a collar for pivotally supporting said pin on said joined flanges, said collar being adjustably connected to said flanges so as to permit said pin to be adjusted in any direction with respect to said piston elements.

4. In an internal combustion engine, the combination with a plurality of cylinder units arranged in opposed pairs, of a plurality of piston units, each piston unit being 60 arranged to reciprocate in an opposed pair of said cylinder units, a sector flange secured to each of said piston units intermediate the ends thereof, each of said sector flanges abutting against each other and having their 65 juxtaposed corners cut away internally so

as to form an internal opening, a crank shaft, a connecting rod mounted on said crank, a pin on said connecting rod, and a collar supported on said flanges so as to mount said pin in said internal opening 70 whereby said connecting rod is pivotally connected with said flanges.

5. In an internal combustion engine, the combination with a plurality of cylinder units arranged in two opposed sets of four quadrantly disposed units, of a plurality of piston units, each piston unit being arranged to reciprocate in a pair of opposed cylinder units, a quadrant sector flange formed integral with each of said piston units intermediate the ends thereof, means to secure said quadrant flanges together so as to form of said piston units a composite piston the parts of which are rigidly secured together so as to move in unison, each of said quadrant flanges being cut away at its inwardly facing corner so as to form an internal circular opening, a crank shaft, a connecting rod mounted on said crank shaft, a pin on said connecting rod, and a collar mounted 80 on said flanges and forming a means of connection for said pin to said flanges whereby the connecting rod is pivotally connected with said composite piston.

6. In an internal combustion engine, the combination with a plurality of cylinder units arranged in two opposed sets of four quadrantly disposed units, of a plurality of piston units, each piston unit being arranged to reciprocate in a pair of opposed cylinder units, a quadrant sector flange formed integral with each of said piston units intermediate the ends thereof, means to secure said quadrant flanges together so as to form of said piston units a composite piston the parts of which are rigidly secured together so as to move in unison, each of said quadrant flanges being cut away at its inwardly facing corner so as to form an internal circular opening, a crank shaft, a connecting rod mounted on said crank shaft, a pin on said connecting rod, and a collar mounted 100 on said flanges and forming a means of connection for said pin to said flanges, whereby the connecting rod is pivotally connected 105 with said composite piston, said collar being circular and adjustable in said circular opening so as to permit an adjustment of said pin relative to the units of said composite piston.

7. In an internal combustion engine, the combination with a plurality of cylinder units, of a composite piston having a plurality of piston units co-operating with said cylinder units, means for securing said piston units to move in unison, a crank shaft, a connecting rod mounted on said crank shaft, a pin on said connecting rod for pivotally connecting said rod with the piston units, and an adjustable support for said pin 120 125 130

on said means whereby the relative position of said pin with respect to the elements of said composite piston can be varied.

8. In an internal combustion engine, the combination with a plurality of cylinder units, of a composite piston comprising a plurality of piston elements having a continuous cylindrical surface, a flange formed integral with each piston element intermediate the ends thereof, each of said flanges being cut out so as to form a circular open-

ing when joined together, means for securing said flanges together, and a collar mounted in said circular opening.

In witness whereof I have hereunto set my hand this 19th day of July, 1912, in the presence of two witnesses.

ALMON B. CALKINS.
